CLAIM

The ornamental design for an inhaler cartridge, as shown.

DESCRIPTION

FIG. 1 is a bottom view of an inhaler cartridge showing our new design;

FIG. 2 is a rear view of FIG. 1;

FIG. 3 is a top view of FIG. 1;

FIG. 4 is a right side view of FIG. 1;

FIG. 5 is a left side view of FIG. 1;

FIG. 6 is perspective view of FIG. 1; and,

FIG. 7 is a front view of FIG. 1.

(Continued)

The broken lines in the drawings illustrate portions of the inhaler cartridge that form no part of the claimed design.

1 Claim, 7 Drawing Sheets
